[57] **ABSTRACT**

Polymethylene polyamine sulfonamides of alkyl-substituted phenolic sulfonic acids wherein the alkyl-substituent has a molecular weight within the range of 400 to 3000 are novel compounds soluble in mineral hydrocarbon oils of the lubricating oil range and as solutes therein are ashless addition agents imparting to the solution a combination of anti-oxidant and detergency-dispersancy properties useful in the lubrication of internal combustion engines. Illustrative of such sulfonamides are mono- and disulfonamides of hexamethylene diamine, tetraethylene pentamine, 2,6-di(aminoethyl) pyridine and N,N'-di(aminopropyl) piperazine with 4-alkylphenolic sulfonic acids such as 4-alkyl-1-hydroxyphenyl, 4,4'-dialkyl-1,1'-dihydroxy-2,2'-biphenyl, 4-alkyl-1-alkoxyphenyl or 2-tri- and tetra-(4'-alkyl-1-hydroxybenzyl)-substituted 4-alkyl-1-hydroxyphenyl sulfonic acid chlorides.

1

MINERAL LUBRICATING OIL CONTAINING HIGH MOLECULAR WEIGHT ALKYL SUBSTITUTED PHENOLIC SULFONAMIDE

BACKGROUND OF THE INVENTION

Sulfonamides of aromatic hydrocarbon sulfonic acids and phenol sulfonic acids having nuclear substituents comprising rather short chain (hence low molecular weight) substituted alkyl groups are known but their limited solubility in mineral oils of lubricating oil types have made them unattractive as additives for formulating lubricant oil compositions. The sulfonamides are nonionic surfactants, are more stable than amine salts of sulfonic acids and are capable of combustion to ash-free (no metallic residue) products. However, their suitability as useful lubricant oil addition agents has been somewhat neglected in part because of their limited solubility in lubricating oils and in part by the lack of sulfonic acid precursors having suitable oil solubilizing characteristics. In a copending application phenolic sulfonic acid affording compounds, i.e. sulfonylides which are intermolecular sulfonic acid esters and sulfonic acid chloride, and their preparation by unique sulfonation and chlorosulfonation are described. Those phenolic sulfonic acid affording compounds because of the nature and character of their alkyl-substituents do permit the preparation of sulfonamides of suitable oil solubility to provide sulfonamides useful in formulating lubricant oil compositions for use in lubricating internal combustion engines where heat stability and ash-free properties of the sulfonamide can be used to advantage.

SUMMARY OF INVENTION

The class of sulfonamides of this invention can be illustrated by the general formula:

wherein X is hydrogen or a group, Y is a divalent polymethylene group having 0 to 1 divalent

Y is a divalent polymethylene group having 0 to 1 divalent pyridyl or piperazinyl bridge between such methylene groups and Z is a 4-alkylphenyl group with the hydroxyl group in the 1-position on the benzene ring. Said sulfonamides are obtained by the reaction of a polymethylene polyamine, hereafter further described, which has two primary amino groups: $\text{H}_2\text{N}-$ and a phenolic sulfonic acid precursor which is a sulfonylide or a sulfonic acid chloride as follows wherein Equation (I) illustrates reaction of equimolar proportions diamine and sulfonylide and Equation (II) illustrates reaction of the diamine with sulfonic acid chloride:

The reaction illustrated by Equation (I) can be modified by the use of two moles of diamine per mole of the sulfonylide to provide a monosulfonamide product. The reaction of Equation (II) also can be modified to provide the disulfonamide product through the use of two moles of phenolic sulfonic acid chloride per mole of diamine.

EMBODIMENTS OF THE INVENTION

Representative diamines include diamino alkanes having from one to 10 divalent methylene groups ($-\text{CH}_2-$) between the amino groups, for example methylene, ethylene, 75

propylene, butylene, pentamethylene, hexamethylene, heptamethylene, octamethylene, nonamethylene and decamethylene diamine; N,N'-disubstituted piperazine and nuclear 2,6-disubstituted pyridine wherein each have the substituents aminomethyl, aminooethyl, aminopropyl, aminobutyl, aminopentyl, aminohexyl, aminoheptyl, aminooctyl, aminononyl, and aminodecyl groups; and polymethylene polyamines of the structure $\text{H}_2\text{N}-[(\text{CH}_2)_m\text{NH}]_n-\text{H}$ WHERE N is a number of from 1 to 10, preferably 2 and 3, and m is a number from 2 to 11. The polymethylene polyamines are polyanalogs of the diaminoalkanes. The preferred polymethylene diamines include di-, tri-, tetra-, penta-, hexa-, hepta-, octa-, nona-, and deca-ethylene and propylene tri-, tetra-, penta-, hexa-, hepta-, octa-, nona-, deca-, and undeca- amines. Also said polymethylene polyamines can be polymers of ethylene imine of 1,000-4,000 molecular weight.

Representative precursors of the phenolic sulfonic acid moiety of the present inventive sulfonamide are as mentioned before aryl sulfonylides and 1-hydroxyphenyl sulfonic acids chlorides having a 4-nuclear alkyl-substituent of 400-3,000 molecular weight.

The alkyl-substituted sulfonylide reactant can be illustrated by the structure of the sulfonylide of 4-alkyl-1-hydroxyphenol 25 as follows:

wherein R is the nuclear alkyl-substituent of 400-3,000 molecular weight. Said alkyl group R can be derived from wax

35 paraffin hydrocarbons wherein the mixture of hydrocarbons have an average molecular weight in the range of 400-3,000. The sulfonylide is obtained by sulfonating with oleum of 20-40 weight percent SO_3 a 4-alkyl-substituted phenol which in turn is obtained by the alkylation of a phenol with a mono-40 chlorinated wax paraffin of suitable size within the range of 400-3,000 molecular weight or with a liquid viscous polypropene or polybutene (propene or butene polymerized in the presence of AlCl_3) of appropriate number average molecular weight (Mn) in the range of 400 to 3,000.

The phenolic sulfonic acid precursor can be 4-alkyl 1-hydroxy-benzene 2-sulfonic acid chloride:

55 or 4-4'-alkyl-1,1'-hydroxy-2,2'-biphenyl-6,6'-disulfonic acid chloride:

60 65 or the 2-tri- and tetra-(4'-alkyl-1-hydroxybenzyl)-substituted 4-alkyl-1-hydroxybenzene sulfonic acid chlorides which are respectively

wherein A is a number of from 2 to 3. Said tri- and tetra-(4'alkyl-1-hydroxybenzyl)-substituted 4-alkyl-1-hydroxybenzene sulfonic acid chloride reactants are obtained by chlorosulfonating the respective products from the condensation of 4 and 5 moles of 4-alkylphenol with formaldehyde. In all of the foregoing R is the nuclear alkyl-substituent of 400 to 3,000 molecular weight.

When the sulfonic acid chloride is the reactant, a hydrogen chloride acceptor which will combine (i.e. as a HCl salt) or react with HCl to form a water soluble product is used. Pyridine is the preferred HCl acceptor. Such combination or reaction product with HCl can be readily removed from the sulfonamide product by water washing since the present inventive sulfonamides are not appreciably soluble in water.

ILLUSTRATIVE EXAMPLES

The following examples will illustrate several species of the present inventive sulfonamides and their preparation as well as their use in lubricant oil compositions.

EXAMPLE 1

There are combined and stirred at ambient temperature 0.1 mole sulfonylide of 4-alkyl-1-hydroxy sulfonic acid wherein the alkyl group is a polypropyl group of 400 Mn and tetraethylene pentamine (TEPA) in the respective molar ratio of reactants of 1.0:2.0. The sulfonylide (1,116 M.W.) is used as a 40 weight percent solution thereof in SAE 5W oil. The stirred mixture is heated to about 120°C. for 1 hour. The reaction product is a solution having 42 weight percent of mono-4-alkyl-1-hydroxybenzene sulfonamide of tetraethylene pentamine and about 3.94 weight percent nitrogen.

EXAMPLE 2

Example 1 is repeated except that 0.2 mole each of the sulfonylide and TEPA are reacted. The resulting product is a 40 weight percent solution of N¹,N⁵-di-4-alkyl-1-hydroxybenzene sulfonamide of TEPA having about 2.25 weight percent nitrogen.

EXAMPLE 3

Example 2 is repeated except the commercial mixtures of polyalkylene polyamines having the molecular weight and nitrogen on the average equal to tetraethylene pentamine but only about 70 percent of the molecules are linear [i.e. H₂N-(C₂H₄-NH)_x-H] and the remaining 30 percent of the molecules have branched aminoethyl groups attached to linear chain, therefor tertiary, nitrogens. The resulting sulfonamide has 2.25 percent nitrogen.

EXAMPLE 4

There are combined and stirred 0.3 mole of 4-alkyl-1-hydroxy-benzene sulfonic acid chloride (alkyl group is 885 Mn polybutyl) and 0.3 mole pentaethylene hexamine (PEHA) dissolved in 200 ccs pyridine in a reaction vessel having, in addition to a stirrer, an inlet for charging liquid, a gas inlet and a gas outlet. The sulfonic acid chloride is charged as a 50 weight percent solution thereof in SAE 5W oil. The solution of PEHA is added rapidly to the stirred solution of the sulfonic acid chloride starting at ambient temperature. After all the PEHA is added the stirred mixture is heated to 130°-135°C., nitrogen gas is injected into the hot liquid to remove pyridine and water in the exhaust gas. Then 56 grams of CaO suspended in 5W oil are added. The dried mixture is filtered. The filtrate solution contains 61 weight percent of the mono-4-alkyl-1-hydroxybenzene sulfonamide of PEHA and about 4 weight percent nitrogen.

EXAMPLE 5

A stirred solution of 430 grams (0.3 mole) 4-alkyl-1-hydroxyphenol sulfonic acid chloride of 1,434.5 Mn (alkyl is polybutyl group of 1,307 Mn), 504 grams SAE 5W oil and

2,000 ml hexane is prepared at ambient temperature in a reactor having a stirrer, electric heat mantle, inlet for charging liquid and gas inlet for introducing gas into liquid contents. To the stirred solution there are rapidly added 60 grams (0.312 mole) TEPA dissolved in 100 ml of pyridine and 20 grams sodium hydroxide dissolved in 50 ml. of water. Thereafter the mixture is heated to and maintained at a temperature of 300°F. for 1 hour while injecting nitrogen gas into the reaction liquid. The nitrogen gas injection aided the removal of hexane, pyridine and water. The resulting solution of mono-sulfonamide of TEPA in oil is diluted with 200 grams of SAE 5W oil (704 grams total oil) and filtered to remove sodium chloride and unreacted sodium hydroxide. The filtrate contains 40.5 weight percent of N-(4-alkyl-1-hydroxyphenyl) sulfonamide of TEPA and has a nitrogen content of 1.47 weight percent.

EXAMPLES 6 to 9

Following the procedures of Example 4 there are prepared the sulfonamides of the structure:

wherein A is hydrogen or methyl, by reaction of substantially equal molecular proportions of tetraethylene pentamine with the appropriate 4-alkyl-1-hydroxyphenyl sulfonic acid chloride to provide the sulfonamide having the R substituent indicated in Table I by the Mn of the alkyl-substituent R and the nature of A. Table I also indicates the concentration in weight percent of the sulfonamide in SAE 5W oil and the nitrogen content in weight percent of the solution.

TABLE I

Example	A	Type	R-substituent	Oil solution	
				Mn	Sulfonamide concentration, percent
6	Hydrogen	Polybutyl	1,600	44	1.06
7	do	Polypropyl	800	40	2.27
8	Methyl	Polybutyl	1,600	40	1.0
9	Hydrogen	Polypropyl	700	60	2.2

¹ Sulfonamide:

EXAMPLES 10 to 12

Following the procedure of Example 4 there are prepared the sulfonamides of the structure:

by reaction of substantially equal molecular proportions of pentaethylene hexamine with the appropriate 4-alkyl-1-hydroxyphenyl sulfonic acid chloride to provide the R group substituent indicated in Table II which also indicates the weight percent concentration of the sulfonamide and nitrogen content of the SAE 5W oil solution.

TABLE II

Example	R-Substituent	Mn	Oil Solution Sulfonamide Concentration	Nitrogen Content
10	polybutyl	1600	33.5	1.21
11	polybutyl	960	61	4.02
12	polypropyl	700	40	2.72

The utility of the present inventive sulfonamides can be demonstrated by their use in lubricating oils which are subjected to low severity dispersancy test, high severity dispersancy test. Those tests are conducted in the following manners.

Low Severity Dispersancy Test

A measured amount of sulfonamide is dissolved in 20 grams of used crankcase oil containing sludge. The mixture is stirred and heated to 300°F. and held at that temperature for 3 hours. Five drops of hot oil (300°F.) are spotted on blotter paper and held at ambient temperature (about 77°F.) After 3, 19 and 150 hours at ambient temperature, each spot is measured with respect to outer clear oil ring and inner concentric sludge ring. The ratio of sludge ring area to oil ring area X100 is determined as a number evaluation of sludge dispersing efficiency.

High Severity Dispersancy Test

This test is similar to the Low Severity Dispersancy Test except the mixture of sludge in oil solution of candidate sulfonamide is stirred and heated to 320°F. for 20 hours before the drops were spotted on blotter paper which is then held at ambient temperature for 3 hours, 19 hours and 12 days before measuring the clear oil ring and sludge ring and determining their areas for calculating the ratio of said areas X100 to obtain dispersing efficiency number value.

The results of those two tests are reported in Tables IV and V below for the use of candidates selected from the foregoing sulfonamide examples. Sulfonamide concentration in the used crankcase oil (20 grams) is replaced in grams of sulfonamide per 20 grams of sludgy used crankcase oil.

TABLE IV

Low Severity Dispersancy Test		Hours After Spot Deposit		
Example	Sulfonamide Tested Concentration		3	19
Control	0	54	54	54
6	1	not measured	65	54
7	1	not measured	73	58 ^(a)
7	2	100	100	74 ^(a)
11	1	not measured	78	56 ^(a)
11	2	100	100	86 ^(a)

^(a)Three weeks after spot deposit.

^(b)240 Hours after spot deposit.

^(c)240 Hours after spot deposit and 77 after 30 days.

TABLE V

High Severity Dispersancy Test		Time After Spot Deposit		
Example	Sulfonamide Tested Concentration		3 hr.	19 hr.
7	1	86	66	55
7	2	100	not measured	81
11	1	80	64	56
11	2	100	100	88
12	1	100	68	58
12	2	100	100	83

EXAMPLE 13

The monosulfonamide of N,N'-di(aminopropyl) piperazine and 4-alkyl (Mn 2,000 polybutyl)-1-hydroxyphenyl sulfonic acid having the structure:

5

6

wherein R is said 2,000 Mn polybutyl group is prepared using SAE-5W oil diluted as described in Example 3. The oil solution contains about 40 percent sulfonamide and 1.0 percent nitrogen on a weight basis.

The oil solution of the sulfonamide of Example 13 is used to supply detergent for the following crankcase oil formulation wherein the ingredients named are used on a volume percent basis.

Ingredient	Amount-Vol. %
Oil solution product of Example 13	4.5%
Oil solution of zinc salt of dialkyldithiophosphate	0.7%
Oil solution of calcium alkylbenzene sulfonate	1.5%
SAE 30 base stock oil	93.3%
Total:	100.0%

The zinc dialkyldithiophosphate used had primary alkyl groups and the zinc salt content of the oil solution is 80 percent by weight. The calcium alkylbenzene sulfonate oil solution contained 40 weight percent of the calcium salt.

The above oil formulation using the product of Example 13 is used as crankcase lubricant in a Caterpillar Diesel Engine operated under the standardized Caterpillar Engine Test 1H conditions for 240 hours. At the end of this test the efficiency of in-service use of said crankcase oil formulation was evaluated by inspection of engine piston with respect to deposits in top ring groove, on first land and in second ring groove. The results found are:

35	Top Groove Filling	2%
	First Land Coating	60%
	Second Groove Filling	50%

40 Use of the same crankcase oil formulation without the sulfonamide would result in 25 percent fill of top groove, 60 percent coating of first land and 70 percent fill of second groove.

EXAMPLE 14

45 The process of Example 1 is repeated using a 4-polypropyl-1-hydroxy benzene sulphonyl chloride (polypropyl group has Mn 753) and TEPA in a 0.5:1.0 mole ratio. The resulting sulphonamide of TEPA has a Mn of 1,097. The product resulting from this example contains 42 weight percent of said sulphonamide and has a nitrogen content of about 2.3 weight percent.

EXAMPLE 15

55 The process of Example 14 is repeated using a 4-polypropyl-1-hydroxy benzene sulphonyl chloride (polypropyl group has Mn 753) and TEPA in a 1.0:1.0 mole ratio. The resulting disulphonamide has a Mn of 2,010. The product from this example contains about 40 percent of said disulphonamide and has a nitrogen content of 1.2 weight percent.

60 What is claimed is:

1. A mineral lubricating oil composition having dissolved therein 33-60 weight percent of said composition of high molecular weight alkyl-substituted phenolic sulfonamide of the formula:

70 wherein X is hydrogen or the

group;

Y is polyaminoethylene group having two to 10 $-C_2H_4-$ groups joined by one to nine $-NH-$ groups or N,N-di(propene) piperazine; and Z is 4-alkylphenyl group wherein the alkyl group has a molecular weight from 400 to 3,000.

2. The composition of claim 1 wherein the alkyl substituent of Z is polypropyl or polybutyl of 400-3,000 M_n .

3. The composition of claim 2 wherein Y is N,N'-di(propylene) piperazine and X is hydrogen.

4. The composition of claim 2 wherein Y is $+C_2H_4NH+$ 10

and X is hydrogen.

5. The composition of claim 2 wherein Y is $+C_2H_4NH+$,

X is

and Z is said 4-alkylphenyl.
